Atty.

UNITED STATES PATENT OFFICE.

JOHN R. HOLMES, JR., OF PASADENA, CALIFORNIA.

GAS-BURNER HEATER.

1,206,328.

Specification of Letters Patent. Patented Nov. 28, 1916.

Application filed February 23, 1916. Serial No. 80,936.

To all whom it may concern:

Be it known that I, JOHN R. HOLMES, Jr., a citizen of the United States, residing at Pasadena, in the county of Los Angeles and 5 State of California, have invented new and useful Improvements in Gas-Burning Heaters, of which the following is a specification.

My invention relates to a gas burning heater.

- 10 It is an object of this invention to construct a gas burning floor heater which is arranged below the floor of a room to be heated and which is economical in gas consumption with a maximum of heating capacity. The same is constructed with a 15 large radiating surface, whereby the maximum quantity of heat for heating the room is abstracted from the hot gases before they pass out into the waste gas flue.
- 20 Another object of this invention is to construct a heater having provisions for the positive circulation of the air to be heated, so that a large volume of air will flow in contact with the heating surface thereof, 25 thereby insuring a rapid heating of the room. For this purpose I provide a vertical burner chamber which communicates at the top with a plurality of radiator sections having the shape of annular chambers, the 30 last radiator section being provided with a vent pipe for conducting the waste gases to the atmosphere. A regulatable air supply valve for the burner is provided whereby the air for combustion may be easily controlled.
- 35 The burner section chamber has preferably a layer of fire clay balls for retaining and equalizing the heat.

With the above and other objects in view, my invention consists in the construction, 40 arrangement and combination of parts hereinafter described and claimed.

In the accompanying drawings forming a part of this specification, I have illustrated a convenient and practical embodiment of 45 my invention, and in which:

Figure 1 is a side elevation partly in section of my floor heater. Fig. 2 is a top plan view thereof with part of the register being broken away. Fig. 3 is an enlarged detail 50 view on line 3—3, Fig. 1. Fig. 4 is an enlarged vertical section of the top of the burner chamber.

In the drawings, 10 represents a box shaped metal casing rectangular in cross 55 section and open at the top which is ar-

ranged below the floor of the room to be heated. The register plate 11 which forms a cover for said casing is flush with the floor of the room. One of the side walls of said casing 10 is provided near its lower end with 60 an aperture 12 which may be connected with a suitable conduit outside the house for supplying air to the heater. The heater proper consists of a burner chamber 13 and a plurality of radiator sections 14. I have shown 65 three radiator sections, but it will be understood that the number may be varied, the consideration determining the number of radiator sections will be whether the cost of the additional radiator sections will be compensated for by the additional number of 70 heat units abstracted from the hot gases before they pass out into the waste flue.

The burner and the radiator sections are cylindrical in shape and of the same height 75 and diameter. They are suitably mounted in spaced relation to the casing 10, there being a horizontal air chamber 15 extending between the bottom of the casing 10 and the lower ends of the burner and radiator 80 sections. The burner chamber consists of a cylindrical casing 16 which is open at the bottom and closed at the top, a small circular removable mica window 17 being centrally provided at the top for observing the 85 burning within said chamber. A radially slotted air valve 18 comprising a stationary member 19 and a rotatable member 20 is mounted transversely across the bottom of the burner chamber 13. The rotatable member 20 is adjusted when the heater is installed to furnish the proper amount of air 90 for complete combustion of the gas in the burner chamber. However the air valve is not essential and may be omitted altogether. 95 In the burner chamber 13, a Bunsen burner 24 of any suitable construction is mounted which is connected to a gas main by pipe 25. A gas cock 26 is provided in said pipe which is operated by a vertical rod 27 extending 100 to the register, said valve being provided with a minute opening so that a pilot flame will be burning in said burner when the valve is totally closed. The rod 27 has a handle 27' at its upper end which may be grasped to draw the rod up or down and operate the valve 26.

A horizontal metal screen 28 is mounted 105 in the burner chamber 13 above the Bunsen burner which supports a layer of fire clay 110

balls 29 which serve to retain the heat and also facilitate and effect a perfect combustion of the fuel gases.

A short connecting passage 30 leads from the upper end of the burner chamber to the top of the adjacent radiator section 14. The radiator sections 14 are of the shape of annular chambers closed at the top and bottom, each pair of adjacent radiator sections being in communication by a vertical passage 31 extending the whole height of said sections. This construction of the radiator sections provides a vertical cylindrical air heating chamber 32 open at the top and bottom, whereby the cold air entering through the aperture 12 in the air chamber 15 rises and becomes heated during its passage, and enters the room through the register 11. The last radiator section 14 has an outlet port 33 near the bottom thereof, through which the waste gases pass out through a vent pipe or waste gas off-take flue 34. This off-take flue 34 is connected to a chimney or leads out to the atmosphere.

It may occur that when the burner is first started, and especially in case where there are many radiator sections, that the waste gases will not be easily taken off through the vent pipe 34. To overcome this difficulty, I provide a by-pass 35 connecting the top of the last radiator section with said vent pipe. The waste gases will flow through this by-pass without any difficulty since there is a practically horizontal passage from the top of the burner chamber to said by-pass. As soon as a good draft is established, the by-pass 35 is closed by means of a damper 36 operated by a handle 37.

In the operation of the floor heater the gas cock 26 is opened, thereby starting the Bunsen burner 24, which is ignited by the pilot flame. The hot gases rise and flow to the top of the burning chamber to the adjacent radiator section, where they will be distributed throughout the intercommunicating radiator sections, a portion of said gases flowing near the top of said sections, while the remaining portion will flow downwardly until all the gases reach the last radiator section, where they pass out through the vent pipe 34. The heating gases are now considerably cooler because of the heat units extracted therefrom by the air currents flowing upwardly through the central air chambers 32 and between the side walls of the outer casing 10 and the outer walls of the radiator sections.

It should be noted that the hot gases in their progress not only rise in the burner chamber and descend in the annular radiating chambers, but that they must pass in turn around each vertical air heating chamber 32; and also that said hot gases in passing from each radiator section to the next are compelled to strike at right angles

against the central tube forming the walls of each air heating chamber 32.

While I have shown my air heater embodied in the form of a floor heater, it will be understood that the same may be used also as a wall heater, in which a vertical register will be used in place of a horizontal one as will be understood, and other obvious changes necessary to adapt the heater to such location.

I prefer to cast the burner chamber and the radiator sections in two vertical halves so that the vertical and horizontal flanges 38 suitably fastened together and made gas tight will run along the vertical sides and 75 the top and bottom as shown in Fig. 2.

While I have shown the preferred construction of the heater as at present known to me, I do not desire to confine myself to the specific construction of the heater as 80 shown and described as various changes in the arrangement and construction of the parts thereof may be made without departing from the spirit of my invention as defined in the appended claims.

I claim:

1. A heater comprising a casing having a register on top, an air inlet near the bottom of said casing, a burner chamber and a plurality of vertical tubular radiator sections mounted within said casing and in spaced relation thereto, a vertical air pipe open at both ends, centrally disposed in each of said radiator sections, each pair of adjacent radiator sections being connected by a passage extending throughout the height of said sections, a passage connecting the top of said burner chamber with the top of the adjacent radiator section, a waste gas off-take flue leading from the last radiator section, a burner in the lower end of said burner chamber and valve controlled means for supplying fuel to said burner.

2. A heater comprising a casing having a register, an air inlet in said casing at a point remote from said register, a burner chamber and a plurality of vertical tubular radiator sections mounted within said casing and in spaced relation thereto, a vertical air pipe open at both ends, centrally disposed in each of said radiator sections, each pair of adjacent radiator sections being connected by a passage extending throughout the length of said sections, a passage connecting the top of said burner chamber with the top of the adjacent radiator section, a waste gas off-take flue leading from the bottom of the last radiator section, a burner in the lower end of said burner chamber and valve controlled means for supplying fuel thereto.

3. A heater comprising a burner chamber, a plurality of tubular radiators, a tube extending through each of said radiators open at the top and bottom so that air may pass

therethrough, said burner chamber communicating at the top with the top of the adjacent radiator, each pair of adjacent radiators being connected by a passage extending throughout the height thereof, a burner in said burner chamber, means for supplying fuel to said burner, means for supplying air to said burner, a waste gas off-take leading from the lower end of the radiator farthest from said burner, and a register plate extending over the top of the heater.

In testimony whereof I have signed my name to this specification.

JOHN R. HOLMES, Jr.
